(57) **CLAIM**

The ornamental design for an electric wire protector as shown and described.

DESCRIPTION

FIG. 1 is a left, front, and top perspective view of electric wire protector,
FIG. 2 is a front elevational view thereof,
FIG. 3 is a rear elevational view thereof,
FIG. 4 is a left side elevational view thereof,
FIG. 5 is a right side elevational view thereof,
FIG. 6 is a top plan view thereof,
FIG. 7 is a bottom plan view thereof,
FIG. 8 is an 8-8 portion enlarged view thereof,
FIG. 9 is a 9-9 portion enlarged view thereof,
FIG. 10 is a 10-10 portion enlarged view thereof,
FIG. 11 is an enlarged left side elevational view thereof,
FIG. 12 is an enlarged right side elevational view thereof,
FIG. 13 is a 13-13 portion enlarged view thereof,
FIG. 14 is a 14-14 portion enlarged view thereof,
FIG. 15 is an enlarged 15-15 line sectional view thereof; and,
FIG. 16 is an enlarged 16-16 line sectional view thereof.
The broken lines shown in the drawings illustrate portions of the electric wire protector that form no part of the claimed design. The chain lines in the drawings are for the purpose of illustrating the boundary between the claimed portions and the unclaimed portions.

1 Claim, 5 Drawing Sheets
